[57] CLAIM

The ornamental design for a combined automobile cover and aerodynamically shaped housing, as shown and described.

DESCRIPTION

FIG. 1 is a top elevation view of a combined automobile cover and aerodynamically shaped housing, showing my new design;

FIG. 2 is a bottom elevation view thereof;

FIG. 3 is a side elevation view thereof;

FIG. 4 is a front elevation view thereof;

FIG. 5 is a back elevation view thereof;

FIG. 6 is a perspective view of a combined automobile cover and aerodynamically shaped housing showing my new design;

FIG. 7 is a reduced perspective view of a combined automobile cover and aerodynamically shaped housing shown mounted on an automobile; and,

FIG. 8 a reduced perspective view of a combined automobile cover and aerodynamically shaped housing shown mounted on an automobile with the cover extracted from the housing. The broken lines in FIGS. 7 and 8 are for purposes of illustration only and form no part of the claimed design.
